UNITED STATES PATENT OFFICE.

THOMAS WILLIAM RUSE AND ERNEST ARTHUR COX, OF PERTH, WESTERN AUSTRALIA, AUSTRALIA, ASSIGNORS OF ONE-THIRD TO ROBERT GLENN, OF MOUNT HAWTHORN, NEAR PERTH, AUSTRALIA.

CONVERTIBLE DINING AND BILLIARD TABLE.

Application filed December 15, 1926, Serial No. 154,939, and in Australia September 20, 1926.

The object of this invention is to render a dining table capable of being convertible for use as a billiard table, thereby adapting an ordinary dining table for the playing thereon of billiards, pool, snooker or like games.

The invention essentially consists in the employment of side and end cushions which are adapted to be removably attached to each other by means of brackets which are formed with dowels adapted to make downward entry into holes formed therefor in the cushions, and which brackets act as frames for the pockets—said cushions when attached to each other as a unit being removably held on the table top by means of clamping brackets.

In order that the invention may be clearly understood, reference will be made to the attached drawings, wherein Fig. 1 is a plan view showing our invention as secured to a table top, one pocket and bracket being removed. Fig. 2 is an enlarged section on line 5—5 of Fig. 1, showing the clamping bracket. Fig. 3 is a plan view of a pocket bracket for use with a large sized table. Fig. 4 is an enlarged section on line 6—6 of Fig. 3.

Referring to said drawings:

We employ removable side and end billiard table cushions as *a* and *b* respectively, of approved make and shape or section, and said cushions may be made of wood, rubber or any other suitable material.

These cushions are held together on the table top *c* by brackets, whose terminals *d* are integrally formed with downwardly extending dowels or pins *e* which are adapted to make entry into vertical holes *f* formed therefor in the end portions of the cushions *a* and *b*. Each of said brackets are made with an outwardly extending curved portion *g* to which the pocket *j* is attached. In connection with said removable cushions, we employ a removable cloth or piece of felt *k*, suitable for the playing thereon of billiards or the like, and which cloth or felt *k* is held in position by being gripped between the cushions *a*—*b* and the table top *c*.

The curved portions *g* of the brackets *d*—*g* downwardly extend to the level of the table top *c* in order that when a large sized table is used, the pockets *j* may be dispensed

with and the billiard balls retained on the table within the said curved portion *g*, as 55 seen in Fig. 4.

To secure the cushions on the table, we employ clamping brackets, whose **U** shaped portions *m* grip the top of the table, while the upstanding rectangular portions *n* abut against the outer face of the cushions, said brackets being secured in position to the table by screw studs *p* which make holding contact against the underside of the table top *c* as particularly seen in Fig. 2. 60 65

When it is desired to use the table for dining or like purposes, the cushions are disassembled by the removal of their holding brackets *d*—*g* and the withdrawal of the dowels or pins *e* from out of the cushions 70 *a*—*b*, while the end clamping brackets are removed by unscrewing the holding studs *p*.

What we claim as our invention and desire to secure by Letters Patent is:

1. A frame for convertible billiard tables comprising two sectional side rails and two end rails, each carrying its respective resilient cushion, the upper face of each rail being provided adjacent each of its ends with two dowel-receiving openings, a plurality of 75 pocket-forming and section and rail connectors, each comprising a net receiving bow having its ends bent into alignment to rest upon the upper surfaces of a pair of adjacent rails and having apertures in said ends 80 to align with the dowel receiving openings 85 of said rails, and removable dowels for insertion in the apertures of the terminals and the openings of the rails to secure said bows and rails together. 90

2. The combination with a table top and a covering therefor, of means for converting the table into a billiard table, comprising two sectional side rails and two end rails, means for connecting the rails together and forming pockets, and clamps each having a pair of parallel arms to embrace the table and cloth and a flat arm extending at an angle to one of said arms to bear against the outer face of one of the end rails to hold 95 said rails in position on the table top. 100

In testimony whereof we have hereunto set our hands.

THOMAS WILLIAM RUSE.
ERNEST ARTHUR COX.
